UNITED STATES PATENT OFFICE

2,306,340

MULTIPLE FUSIBLE CONNECTOR

Marvin Lee, Rye, N. Y., assignor to Burndy Engineering Company, Inc., a corporation of New York

Application September 30, 1939, Serial No. 297,287

5 Claims. (Cl. 200—115.5)

This invention relates to electrical connectors provided with fusible elements, and more particularly to multiple electrical insulated connectors, for conducting current from main to branch conductors, having fusible elements for protecting the insulation of the conductors used for underground secondary network systems.

It is known that considerable economy can be had in forming the fusible elements out of the same piece of metal forming the body of the connector or a part thereof. While this means ordinarily, that if there is a fault in one cable and only one of the fusible elements melts, the entire connector assembly must be discarded, this is not a serious disadvantage because the number of faults are relatively few, so that the economy of making all the multiple fusible connectors integral with the connector body, more than compensates for the extra expense of replacing a few multiple fusible connectors.

As for example, where three branch lines are connected to a main line, a connector having four fusible elements would normally be provided.

I have found that a reserve of one or more fusible elements will provide means for a rapid continuation of the service of any line connected to a fusible element that is blown, without discarding the entire connector.

An object of my invention, therefore, is to provide a connector of the aforesaid type with a bank of reserve integral fusible elements not adapted for immediate use but designed to be placed into general use in the event one of the fusible elements in general use is "blown."

The provision of such reserve fusible elements, I have further found, necessitates the use of readily removable sections of insulation, exposing the ends of the fusible elements for connection to the branch conductors previously attached to "blown" fusible elements, which readily removable sections of insulation, when in position, render the insulation covering the connector, moisture proof and completely insulated.

Thus another object consists in the provision of these aforesaid readily removable sections normally sealing unused fusible elements.

A further object consists in the replacement of these readily removable sections back in the insulating jacket to seal the ends of fusible elements that have been "blown" to keep the connector body completely sealed and insulated.

In the event all the connections are, or have been in use, and one of the elements should thereafter fuse, I have devised a method of re-

5 placing the fused element made integral with the connector, with replaceable fusible elements to be connected with the projecting stem of the connection. This results in a further economy when replacing the fusible elements, and accordingly is an additional object of my invention.

The fusible elements are enclosed within a heat and electrical insulating receptacle for preventing the flow of heat, metal, and/or current from the fused elements. These receptacles must have sufficient structural strength to hold the two ends of the fusible elements in position when fused. In addition the connections must be made to the ends of the elements in a manner which 15 will produce proper electrical contact.

A further object of my invention, therefore, is to provide means for obtaining maximum proper electrical connection of the cable connection and the fusible elements while insuring that the elements when fused, will not loosen the supporting structure.

I accomplish these and other objects and obtain my new results, as will be apparent from the device described in the following specification 25 and claims, and illustrated in the accompanying drawing, in which:

Fig. 1 is a side view of a part of my connector with some of the projecting connections sectioned to indicate their construction.

30 Fig. 2 is a sectional view of my connector taken along the line 2—2, and in the direction indicated by the arrows.

Fig. 3 is a side view of the connector with three out of the six possible connections, in use.

35 Fig. 4 is a plan view of my replaceable fusible element.

Fig. 5 is a side view of a modified connection for a replaceable element.

Referring more particularly to the drawing, 40 reference numeral 10, designates the entire connector, comprising a metallic body section 11, which may consist of strips 12, or a solid bar, to which the fusible elements are integrally attached or formed.

45 An insulating jacket 13, made of insulating material and preferably made of resilient rubber completely encloses the body section.

Extending from the body section 11, are the fusible elements 14, consisting of sheet metal 50 stampings, having a reduced central section 15, of a width, thickness, and composition, determined by the desired fuse characteristics.

The fusible elements are spaced an appropriate distance from each other to provide proper clearance when assembling the conductors thereto,

and to accommodate heat proof enclosures 16, used to confine the arc which results when a fusible section "blows." This not only prevents the arc from damaging the insulation of the connection, it also restrains the products of the arc, such as molten copper, copper vapors, etc. In addition, barriers 17 are located in the enclosure to prevent the arc from striking any molten copper which might accumulate in a pool to the end masses of the fusible connectors. The heat-proof enclosures may be made of a cement and asbestos composition or any other type of suitable material.

As shown in Fig. 2, the fusible elements are provided with apertures 18 and 19 for entrances of bolts 20 passing through corresponding countersunk perforations 21 in the two halves 22 of the heat-proof enclosures 16.

Thus the two halves of the enclosures are each attached to the two ends of the fusible elements and are locked into position thereon by nuts 23.

A terminal connector 25 with extending plate 26 contains perforations 27 and 28. The bolt 20 passes through aperture 28, to lock the terminal to the enclosure. A contact bolt 29, passing through aperture 30 in the extending end of the fusible element, is attached to the terminal plate through apertures 27 which is threaded for such engagement. Thus a pressure is applied to the fusible element, and terminal plate, sufficient to insure maximum electrical conductivity, without passing through the walls of the enclosure and applying a corresponding pressure thereto.

The conductors 32 with insulation 33, are exposed for a short distance and inserted into the terminal connector 25. Any type of terminal connector may be used, the particular type illustrated, consisting of a split flexible compressing cone 34, forced into the tapered recess 35, by bolt 36, centrally apertured to receive the conductor.

The insulating jacket 13 may extend over the enclosures 22 and terminal connector 25, and may be rolled back when the connections are made. I prefer however to use separable sections 37 of tubular resilient material. These are made seal tight to the main body of the insulating jacket 13, by overlapping the ends, as shown in Figs. 1 to 3, and applying cement thereto, or pressure rings, or any other well known expedient.

The reserve units 39 are provided with caps 39 which may be readily severed from their separable tubular section 40, by cutting through the partially detached material at 41, and removed for inserting a conductor therethrough.

These reserve units are preferably provided with terminal connecting means complete, or in part, so that the heat-resisting enclosures 22, need not be removed in order to apply a conductor thereto.

Should an element fuse and no reserve element remain, a further method of continuing the service is possible. The fused element may be filed away to some point, preferably shoulder 40, and a separable element 41 attached thereto, having cut-out portions 42 at each end, for insertion of the bolts 20, which may be tightened to support the separable element and the enclosing receptacle in position.

As shown in Fig. 5, the separable fusible element 43 is shown with apertures 44 and 45 at each end thereof for electrical connection by bolts 46 to the terminal plate of the connector 47, and the remaining section 48.

The bolts 49, hold the enclosures 50 together 75

about the fusible element. With this arrangement, the pressure necessary for establishing proper contact between the fusible element and the connector terminal 47 and section 48, need not be applied to the softer materials of which the enclosure may be made.

I have by the foregoing arrangement secured the economies resulting from a connector formed integrally with the fusible elements, together with advantages obtained by the use of replaceable fusible elements.

An important additional advantage is obtained by the uses of individual heat resistance jackets for each of the fusible elements, and removable insulating covers therefor which may be sealed, thus enabling individual connections to be made and elements replaced without disturbing the remaining connections.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

What I claim and desire to secure by Letters Patent is as follows:

1. A multiple electrical connector for joining main to branch conductors comprising a metallic section of unitary construction; a plurality of fusible elements extending therefrom; an individually removable heat-resistant enclosure for each of said fusible elements; and means for attaching an electrical conductor to each of said fusible elements.

2. A multiple electrical connector for joining main to branch conductors comprising a metallic section of unitary construction; a plurality of fusible elements extending therefrom; an individually removable heat-resistant enclosure for each of said fusible elements; means for attaching an electrical conductor to each of said fusible elements; and insulation completely covering said metallic section, fusible elements, and heat-resistant enclosures, having removable sections of insulating material, at the end of each fusible element for connecting the conductors to said fusible elements.

3. A multiple electrical connector for joining main to branch conductors comprising a metallic section of unitary construction; a plurality of replaceable fusible metallic elements extending therefrom; an individually removable heat-resistant enclosure for each of said fusible elements; means for attaching an electrical conductor to each of said fusible elements; and insulation completely covering said metallic section, fusible elements, and heat-resistant enclosures.

4. A multiple electrical connector for joining main to branch conductors comprising a metallic section of unitary construction; a plurality of fusible elements extending therefrom; a heat-resistant enclosure for said elements, means for attaching an electrical conductor to each of said elements; and insulation completely covering said metallic section, heat-resistant enclosure and fusible elements, provided with openings and

readily removable sections of insulating material covering the openings for a plurality of conductors to be immediately connected to a corresponding number of fusible elements, with the remaining fusible elements completely covered by said insulation.

5. A multiple electrical connector for joining main to branch conductors comprising a metallic section of unitary construction; a plurality of fusible elements extending therefrom having 10

means for detachably securing each element to the metallic section and to its extending conductor; an individually removable heat-resistant enclosure for each of said fusible elements; and bolt like means at each end of the fusible elements; means for attaching an electrical conductor to each of said fusible elements; and insulation completely covering said metallic section, fusible elements, and heat-resistant enclosures.

MARVIN LEE.
